CLAIM

The ornamental design for a refilling device for golf ball washer, as shown and described.

DESCRIPTION

FIG. 1 is a perspective view of a refilling device for golf ball washer showing my new design;

FIG. 2 is a right side elevation thereof;

FIG. 3 is a top plan view thereof;

FIG. 4 is a front elevation thereof; the rear elevation being a mirror image thereof;

FIG. 5 is a left side elevation thereof; and

FIG. 6 is a bottom plan view thereof.

FIG. 1

FIG. 2

FIG. 3

FIG. 4

FIG. 5

FIG. 6
